UNITED STATES PATENT OFFICE.

ROBERT L. CUMNOCK, OF ANDERSON, SOUTH CAROLINA.

SPINNING AND TWISTING APPARATUS.

SPECIFICATION forming part of Letters Patent No. 752,760, dated February 23, 1904.

Application filed August 22, 1903. Serial No. 170,428. (No model.)

To all whom it may concern:

Be it known that I, ROBERT L. CUMNOCK, a citizen of the United States, residing at Anderson, South Carolina, have invented certain new and useful Improvements in Spinning and Twisting Apparatus, of which the following is a specification.

My invention relates to spinning and twisting apparatus, and particularly to means for creating a drag upon the yarn as it passes to the yarn carrier or spindle.

My invention consists in the features and combination and arrangement of parts hereinafter described, and particularly pointed out in the claims.

In the accompanying drawings, Figure 1 is a plan view of one embodiment of my invention. Fig. 2 is a side elevation of Fig. 1, and Fig. 3 is a detail sectional view of a part of Fig. 1. Fig. 4 is a side view of another embodiment of my invention.

In ring-spinning a traveler is generally used for guiding the thread to the rotary spindle and for creating a drag thereon, and it has been found that when the speed of rotation of the spindle is high the traveler is liable to be burned off, owing to the fact that in order to be operative the said traveler must be light in weight, and consequently of a delicate structure. I have aimed to dispense with the use of a traveler and to provide a device which will be efficient in use under all the conditions necessary to be met in ring-spinning and will allow a high speed of the spindle, thus greatly increasing the production of the apparatus.

In the accompanying drawings, 1 indicates a stand, which is suitably secured to a ring-rail of any ordinary form, the said stand supporting thereon at suitable points a series of turnstiles 2, which are free to rotate about their vertical axes and consisting each of a series of radiating arms 3. These stiles support a traveler-ring 4, which in one embodiment of my invention, as shown in Fig. 1, is provided with a groove in its periphery to receive the arms of the stile. By these stiles the ring is supported at different points around its periphery, and I have shown, as an example, three stiles so arranged in connection with the traveler-ring to support the same

and allow it to turn freely. The thread passing to the spindle which projects up through the traveler-ring passes under the said ring, which thus creates the desired drag on the thread, while at the same time the said ring is free to rotate and the thread is free to pass by the stiles, which are constantly turning, owing to the rotary movement of the traveler-ring.

The stiles offer no obstruction to the free passage of the thread, as said thread will fall between the arms of the stiles and will be carried freely past the points where the stiles are supported.

The object of the stiles is not only to support the traveler-ring in proper position, but to allow the free passage of the thread. The weight of the ring is determined by the size of the thread and is such that the ring is virtually held in suspension by the thread. In order to support the stiles, screw-threaded bosses 5 are secured to the stand by means of screws 6, the said bosses supporting sleeves 7, which carry at their upper ends the stiles, said stiles being secured to the sleeves by screws 8. The sleeves have ball-bearings at the upper and lower faces of their flanges 9, and the lower ball-bearings rest in a ball-race formed in the upper face of the boss 5, while the upper ball-bearings are arranged between the upper face of the flange 9 and the adjustable cap 10, which is screw-threaded and is fitted to the exterior of the boss 5. The cap may be held in different positions by a locking-ring 11, screwed onto the boss 5. By this construction the sleeve is adapted to turn freely, so that the stiles carried thereby will be sensitive to the slightest pressure from the thread as said thread passes around the ring. By this construction also the level of the ring may be accurately adjusted. I do not limit myself to any particular means for supporting the stiles, but show that just described as a representative form. The invention may assume different embodiments, and I show in Fig. 4 a different form as illustrating this fact. In this embodiment of my invention the ring is not grooved on its periphery, but is simply a plain ring of light wire. The stiles in this form have their arms bifur-

cated or forked in order to embrace the ring. By this last-mentioned construction a very light ring may be used.

From the above it will be seen that my invention consists, in effect, of a traveler-ring with means for supporting the same, such means offering no obstruction to the free passage of the thread, but being moved aside by contact with the thread to allow the same to pass.

The arms of the stiles are preferably rounded on one edge at 2.

I claim as my invention—

1. In apparatus of the class described, the combination of a traveler-ring having a continuous unobstructed edge for the movement of the thread thereabout and means for supporting the said ring, said means having an interrupted edge and being movable to allow the passage of the thread between the same and the traveler-ring, substantially as described.

2. In combination in apparatus of the class described, a ring and rotary turnstiles for supporting the said ring, said turnstiles allowing the passage of the thread between them and the ring, substantially as described.

3. In combination with a ring having a continuous unobstructed edge for the movement of the thread thereabout, supporting devices arranged around the periphery of the ring, said devices having an interrupted edge and being movable to allow the passage of the thread between the same and the ring, substantially as described.

4. In combination in apparatus of the class described a ring having a continuous unob-

structed edge and movable supporting devices for the said ring, one of said parts fitting in a groove of the other part, substantially as described.

5. An apparatus of the class described, comprising two portions, one portion consisting of a ring and the other consisting of turnstiles for supporting the said ring, one of said portions being grooved to receive the other portion, substantially as described.

6. In combination with a ring, turnstiles for engaging the same and means for adjusting the turnstiles vertically, substantially as described.

7. In combination with a ring turnstiles for supporting the same, threaded bosses arranged on the stand, caps adjustably held on the threaded bosses, flanged sleeves arranged between the caps and the bosses and having ball-bearings, the said sleeves carrying the turnstiles and locking-rings to engage the caps, said locking-rings being screwed on the bosses, substantially as described.

8. In combination a movable ring having its peripheral surface for guiding the thread and rotary devices for supporting the ring, said devices being arranged around the periphery of the ring and each having spaces adapted to allow the thread to pass between them and the ring, substantially as described.

In testimony whereof I affix my signature in presence of two witnesses.

ROBERT L. CUMNOCK.
